UNITED STATES PATENT OFFICE.

HARRY B. HOPSON, OF SPRINGFIELD, MASSACHUSETTS.

FIRE SCREEN.

Application filed November 6, 1922. Serial No. 599,452.

To all whom it may concern:

Be it known that I, HARRY B. HOPSON, citizen of the United States, residing at Springfield, in the county of Hampden and State of Massachusetts, have invented new and useful Improvements in Fire Screens, of which the following is a specification.

The present invention relates to improvements in screens or fenders for fireplaces.

10 The object of the invention is to provide a fire screen through which the heat from the fire may readily pass from the fireplace into the room while the escape of sparks or embers is effectively prevented.

15 To the accomplishment of this object the invention consists in the improved fire screen hereinafter described and claimed.

20 In the accompanying drawings, illustrating the invention in what is now considered its preferred form—

Fig. 1 is a view, in horizontal section, of the improved fire screen showing it in position in front of a fireplace;

25 Fig. 2 is a section taken along the line 2—2 of Fig. 1; and

Fig. 3 is a front elevational view of the screen.

Referring to the drawings, the improved fire screen is located in front of a fire-place 30 4 and comprises spaced-apart right and left wings 5 and 6, and a central portion 7 which is arranged in front of the wings or flanks 5 and 6 and bridges across the space between them. Both the wings and the central portion 7 of the screen consist of rigid frames which support screen sections preferably of wire mesh such as ordinarily used in fire screen construction, the wire being secured to the supporting frames in any suitable

40 manner. The wings 5 and 6 are of the angular form, in horizontal section, which is shown clearly in Fig. 1, each wing having a front portion 8 which faces the fire-place and a side or end 9 which is disposed at right angles to the front portion 8, the ends 9 terminating in vertical edges adapted to abut against the outwardly facing walls at opposite sides of the fire-place. The front portions of the wings 5 and 6 may curve rearwardly to the plane of the free vertical edges of the ends 9, as shown at 10 in Fig. 2.

45 In the present screen, as in other screens designed for fire-places or the like, a wire mesh is employed of sufficient fineness to insure against the passage of sparks there-

through, and it necessarily follows that the screen materially obstructs the passage of heat from the fire-place into the room. In accordance with the present invention, however, the proximate margins of the wings 5 and 6 are spaced apart edgewise to provide between them a wide opening 11 through which the heat from the fire may freely pass beyond the wings 5 and 6 of the screen. The central screen portion 7 is arranged parallel to the front portions 8 of the wings 5 and 6 and extends in front of the opening 11 to arrest such sparks or embers as may be thrown outwardly through said opening and thus to prevent them from escaping into the room. In order to insure that the central screen portion 7 shall not materially interfere with the passage of heat from the fireplace into the room, said screen portion 7 is offset laterally from the vertical plane of the wings 5 and 6 to provide spaces 12 between the vertical margins of the central screen section 7 and the adjacent vertical margins of the wings 5 and 6, thus affording convenient avenues of escape for the heat. With the above described construction, the central screen section 7 serves as a baffle plate for the heat passing through the opening 11, diverting the heat in opposite directions through the spaces 12 as indicated clearly by the arrows in Figs. 1 and 3. The upper portion of the central screen section or baffle 7 may be curved rearwardly, as indicated at 13 in Fig. 2 to conform to the curvature of the upper part 10 of the wings 5 and 6. By thus curving the upper portions of the baffle section 7 and the wings 5 and 6, the escape of sparks upwardly from the fire-place into the room is effectively prevented.

50 The central screen section 7 is rigidly supported and connected with the other sections of the screen, i. e., the wings 5 and 6, by means of suitable rods 14 which are securely fastened to the frames of the several screen sections and serve to bind all parts of the screen together into a rigid unitary structure. It will be observed that the vertical margins of the central screen section 7 overlap the adjacent margins of the wings 5 and 6 sufficiently to prevent the possible escape 55 into the room of sparks which may be thrown obliquely through the opening 10. By virtue of the above described construction, wherein the screen is provided with the opening 11 at the middle thereof and the 60

baffle section 7 is arranged in front of this opening and spaced laterally from the adjacent portions of the screen, the heat is enabled to pass freely from the fire-place into the room while the escape of sparks into the room is positively prevented.

The invention has been herein described for illustrative purposes in an embodiment at present preferred but the scope of the invention is to be determined from the appended claims rather than from the foregoing description.

Claims:

1. A fire screen comprising right and left screen sections arranged in the same plane and spaced edgewise from one another to provide an unobstructed outlet opening for heat, and a third screen section extending in front of said outlet opening and spaced from the plane of said right and left sections to arrest sparks thrown through said opening and to divert in opposite directions the heat which passes through said opening.

2. A screen for fire-places or the like comprising two fire screen sections spaced edgewise from one another to provide an opening between them for the passage of heat, and a third fire screen section located in front of said opening for arresting sparks which may escape therethrough, said third section overlapping the proximate edges of the other two screen sections but being spaced laterally from said edges to provide unobstructed passageways through which the heat may pass freely from the fire-place into the room.

3. A screen for fire-places or the like comprising right and left wings the front portions of which are disposed in the same vertical plane and are adapted to face the fire-place, said wing portions being spaced from each other horizontally to provide an opening between them for the passage of heat, end portions extending at an angle to said front portions and adapted to abut against the walls at opposite sides of the fire-place, and a central screen section offset forwardly from the plane of the front portions of said wings and rigidly connected thereto, said central section being arranged

in front of said opening to arrest sparks which may escape therethrough and to serve as a baffle to divert the heat in opposite directions so that it may pass into the room without passing through the mesh of the screen sections.

4. A fire screen comprising a main screen portion substantially U-shaped in horizontal section adapted to be placed in front of a fire-place or the like with the ends of the screen abutting the front walls at opposite sides of the fire-place and extending at an angle thereto and with the front of the screen offset forwardly from the plane of the front of the fire-place, the front of said screen having an opening therein for the passage of heat, and a baffle section spaced forwardly from the plane of said opening for diverting in opposite directions the heat which escapes through said opening and for arresting sparks which may escape through said opening, said baffle section being rigidly secured to the front of said main screen portion.

5. A fire screen comprising a main screen portion substantially U-shaped in horizontal section adapted to be placed in front of a fire-place or the like with the ends of the screen abutting the front walls at opposite sides of the fire-place and extending at an angle thereto and with the front of the screen offset forwardly from the plane of the front of the fire-place, the front of said screen having an opening therein for the passage of heat, and a baffle section spaced forwardly from the plane of said opening for diverting in opposite directions the heat which may escape through said opening and for arresting sparks which may escape through said opening, said baffle section being rigidly secured to the front of said main screen portion, the upper portions of said main screen section and of said baffle section being curved rearwardly to abut against the wall at the front of the fire-place.

In testimony whereof I have affixed my signature.

HARRY B. HOPSON.
